CLAIM

The ornamental design for an ergonomically optimized squeegee, as shown and described.

DESCRIPTION

FIG. 1 is a front perspective view of an ergonomically optimized squeegee;

FIG. 2 is a top side plan view thereof which is symmetrical with a bottom side plan view;

FIG. 3 is a right side plan view thereof which is symmetrical with a left side plan view;

FIG. 4 is a front side plan view thereof; and,

FIG. 5 is a rear side plan view thereof.
